UNITED STATES PATENT OFFICE.

JAMES C. GILBERT, OF WINTHROP, MAINE.

SKIRT-HOOP.

Specification of Letters Patent No. 22,868, dated February 8, 1859.

To all whom it may concern:

Be it known that I, JAMES C. GILBERT, of Winthrop, in the county of Kennebec and State of Maine, have invented a new and 5 useful or Improved Hoop for Ladies' Skirts; and I do hereby declare that the same is fully described and represented in the following specification and the accompanying drawings, of which—

10 Figure 1, is an external view of one of the said hoops while Fig. 2, is a longitudinal section of one of its stationary abutments, the inelastic cord, the spools, movable abutments and springs extending between the 15 stationary abutments. Fig. 3 is a side view of one of the stationary abutments showing the manner in which the inelastic cord is passed around and through it.

In the said drawings, A, denotes the hoop 20 it being composed of a series of stationary spools or abutments, a, a, certain movable abutments, b, b, helical springs c, c, and sundry wooden cylinders, d, d, d, strung on an inelastic cord, e. Each of the abutment 25 pieces is constructed with a hole bored axially through it, and with a lateral passage, f, leading out of said hole and through the middle of the abutment piece. The mode of passing the cord through the abutment 30 piece is first to insert it into one end thereof, and draw it through the lateral passage, thence to carry it around the block, or abutment piece and in its groove, one or more times, and thence to pass it, into the lateral 35 passage, and thence forward through the front portion of the axial passage. By drawing the cord tightly, the abutment, a, will be rendered, for all practical purposes, stationary thereon.

40 The movable abutments, b, b, are formed in longitudinal section as shown, in Fig. 4 of the drawings, in order that one may enter the other, and both carry a helical spring having its greatest diameter equal to that of 45 each abutment. Several of these springs and their movable abutments are arranged between each two of the stationary abutments a, a, and on the inelastic cord, e, as shown in the drawings—there being also 50 between each two springs, three or any other suitable number of small spools or cylinders,

ders, d, d, d, which are bored axially for the reception of the cord on which both the movable and stationary abutments are strung. The two extremities of the cord 55 may be fastened in one of the stationary abutments.

This mode of making a skirt hoop has important advantages over others composed of small wooden cylinders or metallic thimbles strung upon an elastic cord or upon an inelastic cord and furnished with springs arranged between them, as the stationary abutments cause the strain of all the springs upon the cord to be divided in such manner 60 that the cord is not near so liable to be broken as would be the case were the stationary abutments dispensed with. Furthermore in case the cord should break between two adjacent ends of any two stationary 65 abutments that part of the hook which is between the opposite ends of the said abutments will remain uninjured.

The above mode of making a skirt hoop insures to it the requisite stiffness, with 70 proper flexibility, and enables it to be bent up, and stowed or packed in small compass—or, in other words, it can be doubled, folded or bent up and pushed aside in almost any manner the wearer may choose preparatory 75 to sitting in a chair or on a seat of any kind, or after she may have seated herself thereon.

An inelastic cord is much better than one which is elastic, as by means of the former and the springs applied between the spools 80 or wooden cylinders strung on the cord, more lateral stiffness to insure the set or standing out of the hoop is obtained and maintained, than when the elasticity is in the cord.

I do not claim a hoop skirt composed of 90 hollow pieces of wood threaded on a cord of elastic material; nor one made of solid pieces of wood united at their ends by some suitable elastic fabric, because such inventions are referred to in the *London Mechanic's Magazine*, Volume 52, published in 1850; nor do I claim a hoop of spools or tubes constructed and strung upon an elastic cord or its equivalent and having their 95 ends formed as shown in the United States 100 patent, numbered 18013, nor do I claim the arrangement of a fastening block at the

junction of the ends of the cord, such block being shown in Fig. 15, of the said patent, but

What I do claim is—

5 In connection with the movable spools and springs placed or strung on the cord, a series of stationary abutment blocks, *a*, *a*, *a* fastened at intervals to the cord and oper-

ating in manner and for the purpose as specified.

In testimony whereof, I have hereunto set my signature.

JAMES C. GILBERT.
